UNITED STATES PATENT OFFICE.

WILLIAM F. HERDRICH, OF CHICAGO, ILLINOIS.

PENCIL-SHARPENER.

No. 874,961.

Specification of Letters Patent.

Patented Dec. 31, 1907.

Application filed March 22, 1907. Serial No. 363,990.

To all whom it may concern:

Be it known that I, WILLIAM F. HERDRICH, a citizen of the United States, residing at Chicago, in the county of Cook and State of Illinois, have invented certain new and useful Improvements in Pencil-Sharpeners, of which the following is a specification.

The object of the present invention is to construct a pencil sharpener which shall be strong and compact and at the same time so formed that it can be stamped or died from a blank of sheet metal, thereby enabling the device to be manufactured at small cost and in an easy and convenient manner.

15 The pencil sharpener is intended to be carried in the pocket and is adapted to be operated by the thumb and finger of one hand, leaving the other hand free for the manipulation of the pencil during the sharpening operation.

20 The invention relates to the construction of the several parts of the sharpener and to the manner of assembling the same; and to the features of construction and combination 25 of parts hereinafter described and claimed.

In the drawings, Figure 1 is a side elevation of the open side of the sharpener; Fig. 2 a side elevation taken at right angles to the view of Fig. 1; Fig. 3 a cross sectional view taken on the line 3—3 of Fig. 1 with the cutter removed; Fig. 4 a similar view taken on line 4—4 of Fig. 1; and Fig. 5 a similar view taken on line 5—5 of Fig. 1.

The pencil sharpener comprises a body 6 of tapered formation, having in its front side a tapered opening 7. The body terminates at its upper end in a tubular neck 8 of suitable size to receive the pencil, and the body terminates at its lower or tapered end in a 10 flared base 9 adapted to receive the thumb of the user. The body has secured thereto, at one side of the tapered opening and in alinement with the slope of the opening, a tubular guideway 10 which has slidably 15 mounted therein a knife blade 11 which bears against the edges of the opening 7 and extends outwardly from and in transverse relation to the tubular guideway, as best shown in Fig. 1. The knife blade has upwardly extending therefrom a shank 12 which terminates at its upper end in a finger piece 13 adapted to be engaged by the first finger of the hand, and the shank within the tubular guideway is surrounded by a coil 20 spring 14, the upper end 15 of which is hooked over the open upper lip of the tubu- lar guideway, the spring being connected with the knife and adapted to raise the same after each depression of the finger piece.

25 The body portion, neck, base and tubular guideway are formed in two sections which are blanked or stamped from a piece of sheet metal and afterwards secured together to give the intended information. The neck, body, base and guideway comprise front sections 16, 17, 18, and 19, respectively, and rear sections 20, 21, 22, and 23, respectively. The edge of the front section is cut away to provide the opening 7, and the front section, above the opening, is provided with a tongue 30 which connects the front section 16 of the neck with the front section of the tubular guideway, and the tongue 24 abuts against and is secured to a similar tongue 25 which connects the rear section 21 of the neck with the rear section of the tubular guideway. The tongues are secured together by means of a rivet 26, and the parts are formed of sufficiently stiff material to retain their shape during the operation of the device. The opposite edges of the front and rear sections of the neck are likewise provided with tongues 27 and 28, respectively, which are secured together by means of a rivet 29. This mode of attaching the parts together holds the contacting edges of the front and rear sections of the device in alinement with one another. In like manner the front section 9 of the base is provided with a tongue 30 which connects the base with the lower end of the front section of the tubular guideway, and the tongue 30 co-operates with a similar tongue 31 which connects the rear section 22 of the base with the rear section 23 of the tubular guideway, the two tongues being secured together by 35 means of a rivet 32. The inner edges of the front and rear sections of the tubular guideway are flared or extended to form lips 33 suitably spaced to provide for the reciprocation of the knife blade 11, and at the same 40 time provide a re-inforcement for the blade, whereby it will be prevented from turning or wabbling. It is preferred to form the tubular guideway in substantially parallel relation with the farther edge of the opening 7, 45 so that, as the knife travels up and down, its outer end will at all times rest upon the farther edge of the opening 7, and this operation, at a slight angle with respect to the projection of the pencil inserted through the 50 neck, serves to give a slight shearing movement to the knife, whereby the cutting oper-

ation is facilitated. The farther edges of the front and rear sections of the base are provided with contacting tongues 34 and 35 which are secured together by means of a 5 rivet 36, which, like the other riveted tongues, serves to secure the parts together.

In use, the pencil sharpener will be held between the thumb and first finger of the hand, the base resting upon the thumb, and 10 the first finger contacting the finger piece 13. The other hand of the user will be free to turn the pencil from time to time during the sharpening operation, which is performed by pressing down the operating rod of the knife, 15 thus shearing or cutting off so much of the pencil as projects out of the opening 7. As the sharpening progresses, the pencil will travel deeper and deeper into the tapered portion of the device, and the knife can be 20 carried down farther and farther until the pencil is completely sharpened. The operation is one which is intended to thoroughly sharpen a pencil without breaking the lead, 25 which is usually broken in attempting to use pencil sharpeners of the turning variety.

By forming the parts in the manner indicated, the cost of the article will be reduced to a minimum, since the entire sharpener, with the exception of the knife and spring, 30 can be died or blanked out of a piece of sheet metal and the parts thereafter secured together in a very easy and rapid manner. The knife and shank can be made from a steel rod, the knife blade being beaten or 35 flattened and thereafter tempered and sharpened, which enables a very good quality of steel to be employed in the sharpener, and at the same time enables the knives to be made in a cheap and easy manner. The device 40 as a whole is extremely simple and at the same time may be made thoroughly strong and rigid, and these characteristics, in addition to the cheapness of cost, render the device suitable as an advertising novelty.

15. What I regard as new and desire to secure by Letters Patent is:

1. A pencil sharpener comprising a tapered body having in one side a tapered opening, a knife blade extending transversely of the 50 opening, a tubular guideway adjacent to the openings, a shank within the tubular guideway to which the knife blade is secured, and a coil spring surrounding the shank and adapted to return it to normal position after 55 each stroke, substantially as described.

2. A pencil sharpener comprising a tapered body formed of front and rear sections and a tubular guideway adjacent to the body and similarly formed, the front and rear sections 60 of the body being connected with the corresponding sections of the guideway by means of tongues, rivets for connecting the tongues together, the body being provided with an opening adjacent to the guideway, a knife 65 blade extending transversely of the opening,

a knife shank connected with the blade and slidably mounted within the tubular guideway, and a spring, within the tubular guideway, adapted to return the knife to normal position after each stroke, substantially as 70 described.

3. A pencil sharpener comprising a tapered body having at its upper end a cylindrical neck, the tapered body being provided with a tapered opening, a tubular guideway adjacent to the opening, the body, neck and guideway being each formed of front and rear sections, the front sections being all integrally formed and the rear sections being all integrally formed, rivets for connecting 80 the front and rear sections together, a knife blade extending transversely of the tapered opening, a shank slidably mounted within the tubular guideway, and a spring within the tubular guideway for returning the knife to 85 normal position after each stroke, substantially as described.

4. A pencil sharpener comprising a tapered body having therein a tapered opening, a flared base at the lower end of the body, a 90 cylindrical neck at the upper end of the body, and a tubular guideway adjacent to the opening in the body, the body, base, neck and guideway being all formed of front and rear sections, the front sections being all integral 95 with one another and the rear sections being likewise integral with one another, means for securing together the front and rear sections, and a knife slidably mounted within the tubular guideway, substantially as described. 100

5. A pencil sharpener comprising a tapered body having therein a tapered opening, a flared base at the lower end of the body, a cylindrical neck at the upper end of the body, a tubular guideway adjacent to the 105 opening in the body, the body, base, neck and guideway being all formed of front and rear sections, the front sections being all integral with one another and the rear sections being likewise integral with one another, 110 means for securing together the front and rear sections, and a knife comprising a blade extending transversely of the opening in the body, a shank in transverse relation to the blade and extending through and out of the 115 tubular guideway, and a spring within the guideway for returning the knife to normal position after each stroke, substantially as described.

6. A pencil sharpener comprising a tapered body having therein a tapered opening, a flared base at the lower end of the body, a cylindrical neck at the upper end of the body, a tubular guideway adjacent to the opening in the body, the body, base, neck and guideway being all formed of front and rear sections, the front sections being all integral 125 with one another and the rear sections being likewise integral with one another, means for securing together the front and rear sections, 130

5 lips formed on the sections of the tubular guideway, a knife blade extending between the lips and transversely of the opening in the body, a shank connected with the blade and slidably mounted within and upwardly projecting from the tubular guideway, and a spring for returning the knife to normal po-

sition after each stroke, substantially as described.
